PRINT FEEDING MECHANISM FOR WRAPPING AND PACKAGING MACHINES

Edward F. Ness, Toledo, Ohio, assignor to Morris Packaging Equipment Company, Toledo, Ohio, a corporation of Ohio

Original application July 16, 1935, Serial No. 31,630. Divided and this application June 25, 1937, Serial No. 150,348

2 Claims. (Cl. 198—34)

This invention relates to article wrapping and packaging machines but more particularly to machines for wrapping individual bars of butter, oleomargarine and the like with relatively thin flexible sheet material such as parchment paper, and packaging one or more wrapped bars into cartons.

This application constitutes a division of Patent 2,111,901, issued March 22, 1938, and entitled "Wrapping and packaging machine," and is concerned particularly with the feeding of prints or bars to the wrapping mechanism.

An object is to produce a new and improved mechanism for advancing bars to the wrapping mechanism in such manner that they are properly spaced from each other so that they may be introduced into the wrapping mechanism in properly timed relation and so that inspection thereof can be conveniently made, an opportunity being afforded to remove damaged bars or prints and replace them with others without interrupting the movement of the several bars.

Other objects and advantages of the invention reside in details of construction, arrangement and operation hereinafter described, and, for purposes of illustration, an embodiment of the invention is shown on the accompanying drawing, in which

Figure 1 is a vertical sectional elevation of a portion of a wrapping and packaging machine showing somewhat diagrammatically the primary bar or print feeder and the conveyor for advancing the individual prints to a vertically moving ram which is operable to advance the individual bars to the wrapping mechanism;

Fig. 2 is a top plan view of the mechanism shown in Figure 1; and

Fig. 3 is a detail view showing the driving mechanism for the chain conveyor.

Referring to the drawing, effort has been made to omit unnecessary disclosure of the parts which tend only to obscure the real invention, but, on the contrary, as many parts have been shown diagrammatically to facilitate understanding of the structure and operation of the mechanism so that the nature and operation of the invention will be readily understood by those skilled in this art.

As shown, the primary feeder A to which the individual bars 10 of butter, oleomargarine or the like, in this instance of one-quarter pound size, are delivered, comprises a movable table 11 which reciprocates between stationary guides 11a, on which opposite ends of the prints 10 rest. Motion is imparted to the table 11 by a rocker arm 12 having a roller 13 at its upper end oper-

ating in a vertically disposed guide 14 fixed to the table, this mechanism operating to reciprocate the table 11 longitudinally. At predetermined points in the swinging movement of the arm 12, the table is raised and lowered; raised during the advancing movement of the prints and lowered during the retracting or retrograde movement of the table. This latter is accomplished by an arm 15, which is pivotally connected at its lower end to a horizontal arm 16, 10 the latter being fixed to a swinging arm 17.

The upper end of the arm 15 has a cam surface 18 to engage the table 11 and carries a roller 19 which is adapted to move in a vertically disposed guide 20 on the table. Connected to the 15 lower end of the rocker arm 12 is a rod 21 and connected to the lower end of the arm 17 is a rod 22, the opposite ends of these rods being driven in any suitable manner to effect the desired movement.

It should be noted that the arm 17 is fixed to a shaft 23 with which a vertical arm 24 is rigid. A link 25 for operating an arm similar to the arm 15 adjacent the forward end of the table extends from the arm 24. A link (not shown) 25 extends from the upper portion of the arm 15 and cooperates with the link 25 for effecting the desired motion.

The bars or prints 10 are thus advanced step by step toward a pusher 27 passing beneath a 30 guide 28 disposed above a stationary platform 29. The prints 10 are pushed upon the platform 29, the foremost print being moved beyond the forward edge of the platform, whereupon the pusher 27 engages its upper surface and pushes it downwardly to the chain conveyor B. A bell crank 30 is driven in any suitable manner by a rod 31 and engages the lower end of the pusher 27 to impart the vertical reciprocatory movement thereto.

The chain conveyor comprises a pair of chains 32 spaced laterally from each other and mounted on the chains is a series of shelves or platforms 33, each being secured at its forward end to a stop member 34. The shelves 33 are arranged in pairs, one being secured to each of the chains, and adjacent the opposite end of each shelf 33 is another stop member 35. The pusher 27 lowers the individual prints 10 so that opposite end portions thereof rest upon the platforms 33. The lugs 34 and 35 afford a safety measure so that when it becomes necessary for the operator to replace a bad or damaged print or bar, he can place it on the chain conveyor in the proper position. It will further be apparent that the chain 55

conveyor is such that the prints delivered there-
to can be readily and conveniently inspected,
thereby to insure that only good prints will be
delivered to the wrapping mechanism. The
5 prints must be placed properly upon the chain
conveyor since the ram which raises them, as
will hereinafter appear, operates in timed rela-
tion to the chain and if the prints are not prop-
erly disposed on the conveyor, they will either
10 not be engaged by the rim or will not be prop-
erly engaged to advance them in the desired
manner.

The chain conveyors are trained over sprock-
ets disposed at opposite ends thereof in the usual
15 manner, and a shaft 36 on which the forward
sprocket is mounted, has a small gear 37 mesh-
ing with a larger gear 38 to which is fixed a
smaller sprocket 39 to receive a chain drive 40
driven in any suitable manner so that the chain
20 conveyor B advances the articles three times as
fast as the primary feeder A. Thus, by spacing
the prints in the manner effected by the chain
conveyor, each print may be inspected by an
operator and if one print is injured or damaged
25 or is otherwise unsuitable for wrapping, it can
be replaced by another one.

The prints 10 are individually lifted from the
chain conveyor B by a vertically movable ram 41
which moves upwardly between the chains 32
30 and engages the undersurface of a print, forc-
ing the same upwardly into the wrapping mech-
anism C. Vertical movement is imparted to the
ram 41 by a rocker arm 42, connected by a link
43 to the lower end of the ram, the latter being
35 guided in its vertical movement by a guide 41a.
Any suitable means may be provided for impart-
ing vertical oscillatory movements to the arm
42 in timed relation to the movement of the
chain conveyor B.

40 Detailed description of the wrapping mech-
anism C is not considered necessary. Suffice it
to say that the individual prints or bars 10 en-
gage relatively thin flexible sheet material such
as parchment paper which is delivered into the
45 path of movement of the print and the print and
sheet material are advanced through folders for
effecting the desired folding operations.

Although the above described mechanism is the
best form known to me at the present time, it is

to be understood that the above description is
given merely by way of illustration, and it is
to be understood that changes in details of con-
struction, arrangement and operation may be
effected without departing from the spirit of the
5 invention especially as defined in the appended
claims.

What I claim is:

1. In an article wrapping and packaging ma-
chine, means for advancing a series of prints 10
of butter or the like to form a row with the prints
substantially in engagement with each other, a
platform to receive the foremost print from
which same is pushed by oncoming prints, a
pusher to engage the foremost print as same is 15
moved from said platform and move same at
substantially right angles to said advancing
means, an endless conveyor to receive at one end
thereof prints from said pusher, said conveyor
comprising a pair of laterally spaced endless 20
chains, relatively movable shelves on said chains
respectively for receiving opposite ends of indi-
vidual prints, and a ram at the opposite end
of said conveyor to engage the underside of a
print and discharge same vertically therefrom. 25

2. In an article wrapping and packaging ma-
chine, means for advancing a series of prints of
butter or the like to form a row with the prints
substantially in engagement with each other, a
platform to receive the foremost print from 30
which same is pushed by oncoming prints, a
pusher to engage the foremost print as same is
moved from said platform and move same at
substantially right angles to said advancing
means, an endless conveyor to receive at one end 35
thereof prints from said pusher, said conveyor
comprising a pair of laterally spaced endless
chains, relatively movable shelves on said chains
respectively for receiving opposite ends of indi-
vidual prints, a spacer indicator on opposite sides 40
of each shelf for predetermining the proper
positioning of each print, means to impart con-
tinuous movement to said conveyor so that the
prints are advanced thereby faster than by said
advancing means, and a ram at the opposite end 45
of said conveyor to engage the underside of a
print and discharge same vertically therefrom.

EDWARD F. NESS.
